Primary Examiner — Elizabeth Albert(57) CLAIM

I claim the ornamental design for a electronic cigarette holder, as shown and described.

DESCRIPTION

FIG. 1 is a perspective view of an electronic cigarette holder showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an exploded perspective view of the electronic cigarette holder.

The broken lines are included for the purpose of showing portions of the electronic cigarette holder that form no part of the claimed design.
